UNITED STATES PATENT OFFICE.

WILHELM B. BRONANDER, OF MONTCLAIR, NEW JERSEY, ASSIGNOR TO AMERICAN MACHINE & FOUNDRY COMPANY, A CORPORATION OF NEW JERSEY.

DEVICE FOR APPLYING REVENUE STAMPS TO PACKAGE-WRAPPING MATERIAL TO PREPARE IT FOR USE IN PACKAGING MACHINES.

Application filed August 12, 1926. Serial No. 128,727.

This invention relates to a device for applying revenue stamps to package wrapping material to prepare it for use in packaging machines, its main object being to prepare and feed to packaging machines the wrapping material, wrappers, or labels, assembled in outspread condition with revenue stamps stuck thereto, preparatory to making a completed cigarette or other package in subsequent folding operations, the wrapping material and stamps being so assembled in outspread condition in order to avoid the difficulties heretofore encountered in making revenue stamps stick to more or less irregularly shaped wrapped packages. With this and other objects not specifically mentioned in view, the invention consists in certain constructions and combinations which will be hereinafter fully described and then specifically set forth in the claims hereunto appended.

In the accompanying drawings, in which like characters of reference indicate the same or like parts, Fig. 1 is a side elevation of a device constructed in accordance with the invention; Fig. 2 is a plan view of the same; Fig. 3 is an end elevation of the same; Figs. 4 and 5 are end views of the stamp feed in its two extreme positions as seen from the line 5—5 in Fig. 1; and Fig. 6 is a side view of the wrapper aligning and ejecting devices.

In carrying the invention into effect, there is provided a source of wrapper material supply, a source of revenue stamp supply, mechanism for assembling in outspread condition wrapping material and stamps drawn from said sources of supply, and means for causing said outspread and assembled wrapping material and stamps to stick together preparatory to use of said wrapping material and stamps in packaging machines. In the best constructions contemplated, the source of wrapping material supply includes a magazine for individual wrappers and means for successively delivering wrappers therefrom to said mechanism; the source of revenue stamp supply includes a magazine

for individual stamps and means for successively delivering stamps therefrom to said mechanism; and the means for causing said outspread and assembled wrapping material and stamps to stick together includes a paste-applying device coactive with said mechanism between said sources of supply. These parts may be widely varied in construction within the scope of the claims, for the particular structure selected to illustrate the invention is but one of many possible concrete embodiments of the same. The invention therefore is not to be restricted to the precise details of the structure shown and described.

Referring to the drawings, Figs. 1 to 3, the device is mounted on the frame of the machine which consists of a rectangular casting 7 having an end upright 8 and side uprights 9 and 10. The wrapper magazine 11, which is stationary, has end plates 12 by means of which it is attached to the uprights 8 of the frame. The stack of wrappers 13 in the magazine rests on a roller 14 whose shaft 15 has a sprocket 16 driven by a chain 17 from a sprocket 18 of a drive shaft 19. The shaft 15 of the roller 14, by means of a gear 20, intermediate gear 21, and gear 22, drives the pull-out rollers 23 which are supported between plates 24, the latter being pivoted on the shaft 15 and adjustably held stationary by screws 25. The plates 24 also carry an adjustable rod 26 upon which are mounted two guides 27 and an intermediate guide 28 for the emerging wrapper. The rollers 23, by the aid of the guides 27 and 28, deliver the wrapper 13 to the endless conveyor 29 running over sprockets 30 and 31, the shaft 32 of the former being adjustable in the frame 7, while the shaft 33 of the latter is fixed.

The endless conveyor 29, at equidistant intervals, is provided with prongs 34 which propel the wrappers at each step of the conveyor. The intermittent motion of the conveyor is derived from a ratchet wheel 35 which is actuated by a pawl 36 carried on the upper arm of a bellcrank 37 and held against the ratchet by a spring 38. The

ratchet 35 is fixedly, and the bellcrank 37 is loosely, mounted on the sprocket shaft 33, and the lower arm of the bellcrank 37 is connected by a rod 39 with an eccentric pin 40 on a disc 41 mounted on the drive shaft 19. While being propelled by the conveyor 29, the wrappers rest on the supporting strips 42 and 43, the side strips 43 being joined to the center strip 42 by cross strips 44, and the center strip 42 being supported by a rod 45 from a cross bar 46 attached to the frame 7. The opposite edges of the wrapper slide on end rails 47 supported by brackets 48 fastened to the cross bar 46 and frame 7.

After being deposited on the conveyor, the wrapper 13 is pushed by the aligning strip 49 against the stop plate 50 attached to the end rail 47 (Fig. 3). The aligning strip 49 (Figs. 2, 3 and 6) is connected by a bar 51 to the upper end of a double bellcrank 52 fulcrumed in a projection 53 of the frame 7, and actuated by a rod 54 attached to an eccentric 55 mounted on a shaft 56 which carries a sprocket 57 driven by a chain 58 from a sprocket 59 on a shaft 60. The shafts 56 and 60 are carried by bearings 61 and 62, respectively, mounted on the frame 7, the shaft 60 having a spiral gear 63 meshing with a gear 64 on a vertical shaft 65. The shaft 65 is supported by bearings 66 and 67, the former of which is attached to the frame 7, and the latter to the upright 9. The shaft 65 is driven by a bevel gear 68 meshing with a gear 69 on the drive shaft 19.

As the wrapper 13 passes under the stamp magazine 70, a stamp 71 is deposited on its edge which has previously been supplied with paste, the stamp being smoothed down and sealed by a brush 72 attached by an arm 73 to the frame of the magazine 70. The stamp magazine has a laterally projecting pin 74 by means of which it is suspended, by a lever 75, from a shaft 76 supported in the uprights 9 and 10, and has a vertical slide 77 movable in a guide 78 fastened to the upright 9.

The shaft 76 is rocked by means of a crank 79 connected by a rod 80 to an eccentric 81 on the drive shaft 19, thereby giving to the stamp magazine a periodic up-and-down motion. The stamp magazine (Figs. 4 and 5) has horizontal side brackets 82 which carry shafts 83 and 84 upon which are mounted levers 85 engaging the stamps 71. On one end of the shaft 83 is mounted a lever 86 carrying a pin 87 engaging a slot in a lever 88 clamped to the shaft 84 on which is also mounted an arm 89 having its free end shaped in hook-fashion, the hook portion engaging with a stop 90 attached to the frame 7 when the magazine slide is in its lowermost position. The pin 87 is pulled upwards against a stop 91 mounted

on the magazine frame by a spring 92 attached to the slide 77, thereby pressing the free ends of the levers 85 against the edges of the stamps 71.

As the wrapper 13 arrives below the stamp magazine 70, the latter comes down on it, the magazine thereby being held stationary while the slide 77 continues to move downward, the levers 85 forcing the stamps clamped between them down upon the wrapper. The lowermost stamp then adheres to the wrapper which has been supplied with paste. In the lowermost position of the slide 77, the arm 89 engages the stop 90, thereby turning the shafts 83 and 84 of the levers 85 and releasing the stamps, the lowermost of which adheres to the wrapper which is held down by suction furnished by a vacuum pump 93 through a hose connection 94 and suction head 95 in one of the rails 47, while the magazine moves up. As soon as the arm 89 leaves the stop 90, the levers 85 re-engage the stamps and move all except the lower most one up in the magazine until the rear side bracket 82 again engages the stop 91, whereupon magazine and slide move up together, the wrapper being meanwhile held down by the suction. By the relative motion between the magazine and its slide, the bulk of the stamps is separated from those below the levers 85, thus releasing the weight from the bottom stamps and making the action of the stamp discharge independent of the height of the stack. The suction pump 93 is attached to the frame 7 and is driven by an eccentric 96 mounted on the drive shaft 19.

The pasting device consists of the stationary paste reservoir 97 having the rotating paste drum 98, and of the swinging paste transfer 99. The paste reservoir 97 is detachably mounted on a bracket 100 attached to the upright 9. It is provided with bearings for the shaft 101 of the paste drum 98, and also carries a scraper 102 which removes the surplus paste from the drum. The drum shaft 101 has a sprocket 103 which is driven by a chain 104 from a sprocket 105 on a shaft 106 journaled in a bearing 107 attached to the frame 7. The shaft 106 is driven by a bevel gear 108 meshing with a bevel gear 109 on a cam shaft 110. The cam shaft 110 is journaled in the frame 7 and has a sprocket 111 which is driven by a chain 112 from a sprocket 113 on the drive shaft 19. The paste transfer 99 is mounted on a shaft 114 supported by a bracket 115 attached to the upright 9. The shaft 114 has a gear 116 meshing with a rack 117 mounted on a vertical slide 118 movable in a guide 119 attached to the frame 7. The lower end of the slide 118 is provided with a lug 120 which, by a link 121, is connected to the free end of a cam lever 122, the latter being fulcrumed at 123 on the frame 7 and carrying the roller 130

124 which is kept in engagement with a cam 125 on the shaft 110 by means of a spring 126 attached to the frame 7. As the lever 122 is moved up and down by the cam 125, the rack 117 turns the gear 116 back and forth, thereby transferring paste from the drum 98 to the wrapper 13 on the rail 47, as shown by dotted lines in Fig. 3.

While being carried from the magazine 11 past the pasting device 97, stamp magazine 70, and stamp sealing brush 72, the wrapper 13 is guided by a wire 127 stretched between brackets 128 and 129 attached to the frame 7. The attachment to the bracket 128 is made adjustable by means of a screw 130, so that the tension of the wire 127 can be regulated from time to time. While being pasted, the wrapper is held in place by a finger 131 attached to a bellcrank lever 132 fulcrumed in a bracket 133 fastened to the upright 10 and carrying a roller 134 held in engagement with a cam 135 on the shaft 110 by a spring 136.

Having passed the brush 72, the stamped wrapper is guided around a drum 137 mounted between the sprockets 31 on the shaft 33, and around edge guides 138 attached to the rails 47, by the guard strip 139 attached to the frame 7, being held in contact with the drum by a tape 140 hung from the stamp magazine supporting shaft 76 and kept in proper tension by the weight 141 attached to its lever end.

On its return passage, the wrapper is supported by the center rail 142 and by the side guides 143 hung by the bridge pieces 144 from the center rail. The latter is supported at one end by a bracket 145 attached to the frame 7, and at the other end by a rod 146, adjustably mounted on a cross bar 147 resting on the bases of the bearings 61 and 62.

Upon reaching the end of its return path, the stamped wrapper is held by a stop 148 adjustably supported on a plate 149 mounted on the rod 146, and is then delivered sideways to a drum 150 on which it is held by a roller 151. The delivering pusher 152 is a part of a slide 153 supported on a guide 154 and connected by a link 155 with the lower arm of the double bellcrank 52 before referred to. The drum 150 is mounted on a shaft 60 supported in bearings 62 to which are fastened forked brackets 156 carrying the roller 151. From the drum 150, the stamped wrapper passes into the folding device of the cigarette packaging machine, not shown, in connection with which the device is used, in which it receives its charge of cigarettes and is folded around them into a finished package.

What is claimed is:

1. The combination with a wrapper support, of a stamp magazine, mechanism producing relative approaching and retreating movements of said support and said maga-

zine whereby stamps are affixed to wrappers, and a suction device holding each wrapper and its stamp during a retreating movement to withdraw said stamp from said magazine.

2. The combination with a wrapper support, of a stamp magazine, mechanism producing relative approaching and retreating movements of said support and said magazine whereby stamps are affixed to wrappers, and a suction device holding each wrapper and its stamp during a retreating movement to withdraw said stamp from said magazine, said relative movements being effected by moving said magazine only.

3. The combination with a wrapper support, of a stamp magazine, mechanism producing relative approaching and retreating movements of said support and said magazine whereby stamps are affixed to wrappers, and a suction device holding each wrapper and its stamp during a retreating movement to withdraw said stamp from said magazine, said support being movable to bring wrappers into the range of action of said mechanism.

4. The combination with a wrapper support, of a stamp magazine, mechanism producing relative approaching and retreating movements of said support and said magazine whereby stamps are affixed to wrappers, and a suction device holding each wrapper and its stamp during a retreating movement to withdraw said stamp from said magazine, said support including an intermittently traveling conveyor successively bringing wrappers into the range of action of said mechanism.

5. The combination with a wrapper support, of a stamp magazine, mechanism producing relative approaching and retreating movements of said support and said magazine whereby stamps are affixed to wrappers, and a suction device holding each wrapper and its stamp during a retreating movement to withdraw said stamp from said magazine, said magazine being operative above a wrapper on said support, and said device being operative below the same.

6. The combination with a wrapper support, of a stamp magazine, mechanism producing relative approaching and retreating movements of said support and said magazine whereby stamps are affixed to wrappers, and a suction device holding each wrapper and its stamp during a retreating movement to withdraw said stamp from said magazine, said relative movements being at right angles to the active surface of said support.

7. The combination with a wrapper support, of a stamp magazine, mechanism producing relative approaching and retreating movements of said support and said magazine whereby stamps are affixed to wrappers, and a suction device holding each wrapper and its stamp during a retreating movement

to withdraw said stamp from said magazine, said support having a horizontal active surface, and said relative movements being in vertical directions.

6 8. The combination with a wrapper support, of a stamp magazine, mechanism producing relative approaching and retreating movements of said support and said magazine whereby stamps are affixed to wrappers, 10 and a suction device holding each wrapper and its stamp during a retreating movement to withdraw said stamp from said magazine, said magazine having spring-actuated and cam-controlled means for supporting a majority of the stamps therein independently of the minority during stamp delivery.

9. The combination with a wrapper support, of a stamp magazine, mechanism producing relative approaching and retreating 20 movements of said support and said magazine whereby stamps are affixed to wrappers, and a suction device holding each wrapper and its stamp during a retreating movement to withdraw said stamp from said magazine, 25 said mechanism including eccentric-actuated means for moving said magazine toward and away from said support.

10. The combination with a wrapper support, of a stamp magazine, mechanism producing relative approaching and retreating 30 movements of said support and said magazine whereby stamps are affixed to wrappers, and a suction device holding each wrapper and its stamp during a retreating movement to withdraw said stamp from said magazine, 35 said magazine being mounted in a slideway, and said mechanism including eccentric-actuated means for moving said magazine in said slideway.

40 11. The combination with a wrapper support, of a stamp magazine, mechanism producing relative approaching and retreating movements of said support and said magazine whereby stamps are affixed to wrappers, 45 and a suction device holding each wrapper and its stamp during a retreating movement to withdraw said stamp from said magazine, said device including a suction head at the stamping station and a pump intermittently establishing suction therein.

50 12. The combination with a wrapper support, of a stamp magazine, mechanism producing relative approaching and retreating movements of said support and said magazine whereby stamps are affixed to wrappers, 55 and a suction device holding each wrapper and its stamp during a retreating movement to withdraw said stamp from said magazine, said device including a suction head at the stamping station and an eccentric-actuated pump connected therewith.

60 13. The combination with a wrapper support, of a stamp magazine, mechanism producing relative approaching and retreating movements of said support and said maga-

zine whereby stamps are affixed to wrappers, a suction device holding each wrapper and its stamp during a retreating movement to withdraw said stamp from said magazine, and means for presenting wrappers to said support.

65 14. The combination with a wrapper support, of a stamp magazine, mechanism producing relative approaching and retreating movements of said support and said magazine whereby stamps are affixed to wrappers, 70 a suction device holding each wrapper and its stamp during a retreating movement to withdraw said stamp from said magazine, a wrapper magazine, and means for transferring wrappers from said wrapper magazine to said support.

75 15. The combination with a wrapper support, of a stamp magazine, mechanism producing relative approaching and retreating movements of said support and said magazine whereby stamps are affixed to wrappers, 80 a suction device holding each wrapper and its stamp during a retreating movement to withdraw said stamp from said magazine, a wrapper magazine, and means for transferring wrappers from said wrapper magazine to said support.

85 16. The combination with a wrapper support, of a stamp magazine, mechanism producing relative approaching and retreating movements of said support and said magazine whereby stamps are affixed to wrappers, 90 a suction device holding each wrapper and its stamp during a retreating movement to withdraw said stamp from said magazine, and means for applying adhesive to wrappers before said mechanism comes into action.

95 17. The combination with a wrapper support, of a stamp magazine, mechanism producing relative approaching and retreating movements of said support and said magazine whereby stamps are affixed to wrappers, 100 a suction device holding each wrapper and its stamp during a retreating movement to withdraw said stamp from said magazine, and means for aligning a wrapper on said support before said mechanism comes into action.

105 18. The combination with a wrapper support, of a stamp magazine, mechanism producing relative approaching and retreating movements of said support and said magazine whereby stamps are affixed to wrappers, 110 a suction device holding each wrapper and its stamp during a retreating movement to withdraw said stamp from said magazine, and eccentric-actuated wrapper aligning means.

115 19. The combination with a wrapper support, of a stamp magazine, mechanism producing relative approaching and retreating movements of said support and said magazine whereby stamps are affixed to 120

wrappers, a suction device holding each wrapper and its stamp during a retreating movement to withdraw said stamp from said magazine, means for presenting wrappers to said support, means for applying adhesive to said wrappers prior to presentation to said magazine, means for aligning said

wrappers on said support, and means for ejecting the stamped wrappers from the machine sidewise.

In testimony whereof, I have signed my name to this specification.

WILHELM B. BRONANDER.
